FIG. 3.

FIG. 2.

Francis R. Hardie
INVENTOR

UNITED STATES PATENT OFFICE

FRANCIS R. HARDIE, OF SALT LAKE COUNTY, UTAH

COMMUNICATING FORM

Application filed January 20, 1930. Serial No. 422,110.

My invention relates to an improvement in communicating forms, and its objects are to reduce the volume of weight and bulk of mail; and to save the time, labor, material and other expense involved in the manufacture and use of envelopes, by dispensing with the latter in transmitting communications of the kind referred to, without revealing the contents thereof to any save the addressee.

10 I attain these objects by the device illustrated in the accompanying drawings, in which Figure 1 is a detailed view, in perspective, of the device or form, showing it as it appears with its folds creased, but 15 unsealed.

Figure 2 represents the back of the form as it appears folded, showing one of the flaps 1, pasted to the back surface of the lower fold 5; the other flap 1, showing as not folded over the end of the lower fold 5, and not sealed thereto.

Figure 3 represents the form as it appears, front view, when folded and sealed.

The form is preferably so cut that the extending flaps 1, of, preferably, the upper fold 2, of the form, extend outwardly from the other folds 6 and 5, of the form.

On the upper fold 2, of the form are placed, preferably, in the center or upper 30 left corner, the name, style, and title 3, of the transmitter, together with words, numerals, and symbols to indicate the character of the communication, its date, and the address of the transmitter.

35 Preferably, on the lower, left corner of the upper fold 2, are placed words, numerals, and symbols to indicate the name, style, and title 4, and address of the addressee of the communication.

40 The extending flaps 1, of the form are, preferably, so arranged as to fold backwardly from the front surface of the upper fold 2, of the form, and are so prepared, preferably by gumming, as to be easily 45 sealed or fastened after the form has been folded.

The form is, preferably, folded in three 50 folds, the lower fold 5, of the form, folds, preferably, inwardly and upwardly toward the front surface of fold 6, thus concealing

the contents of the communication which is written on the front surface of folds 6 and 5, of the form.

The center fold 6, of the form is, preferably, folded backwardly and upwardly so 55 that it meets and presses against the back surface of the upper fold 2 thus forming a pocket between the backs of the folds 6 and 2, which may be utilized unsealed or otherwise. The extending flaps 1, are then folded, preferably, backwardly from the front surface of the upper fold 2, and are fastened or sealed, preferably, by gumming, so that the gummed surface of the flaps 1, adhere to the back surface of the lower fold 5, of the 60 form, thus partly sealing the communication.

The end 7, of the lower fold 5, of the form is so arranged, folded, and prepared, that it meets flush and evenly with the upper crease of the center fold 6, on a horizontal line between the address of the addressee, and the salutation of the communication, and on the front surface of the center fold 6. 70

The end 7, of the lower fold 5, of the form 75 is so prepared, preferably by gumming, that it readily fastens or adheres to the extreme upper front surface of the center fold 6, of the form, on a line just above the salutation, and between the latter and the address of 80 the addressee of the communication, thus completing the sealing of the communication, as may be desired, as for example, when sending as first class mail.

If it is desired to send the communication at a cost lower than first class mail, only the extending flaps 1, of the form need be sealed. The form, in such case, being only 85 partly sealed, postal inspection can be easily made.

90 Preferably at either of the sides 8, of the end 7, may be left, preferably unsealed, a very small part of the lower fold 5, of the form in order that the point of a paper cutter, or other instrument, may be inserted 95 for the purpose of opening the communication, and words or indicators are so placed, preferably on the back surface of the lower fold 5, as to attract attention to this con- 100

venient point for opening the form or communication.

On the front surface of the form, preferably on the center and lower folds 6 and 5, respectively, is placed any communication which it is desired to transmit, and thereafter, by folding and fastening or sealing in the manner hereinbefore described, such communication can be transmitted without revealing the contents thereof, and without the use of an envelope.

On the form, preferably at the upper right corner of the front surface of the upper fold 2, is placed a stamp 9 or words or indicators 15 to show that the communication is entitled to be transmitted—for example, when transmitted under mailing permit without stamps affixed, or otherwise.

Having thus described my invention, I desire to secure by Letters Patent and claim:

1. A communicating form of the kind described, consisting of a sheet of paper, or other material, so cut and arranged that flaps extend outwardly from the sides of the upper fold of the sheet, the flaps being so arranged and prepared, preferably by gumming, that when the sheet is folded, the extending flaps fold backwardly from the front surface of the upper fold of the sheet, and may be fastened or be made to adhere to the back surface of the lower fold of the sheet, thereby partly sealing the communicating form, the method of folding forming a pocket between the backs of the upper and middle folds of the sheet which may be utilized unsealed or otherwise, having the name and address of the transmitter of the communication exposed to view on the front surface of the upper fold of the letter sheet, having the lower end of the lower fold of the sheet so prepared, preferably by gumming, that when the lower fold of the sheet is folded upwardly against the front surface of the middle fold of the sheet, the lower, prepared end adheres or fastens to the front surface of the letter sheet, substantially along the upper crease of the middle fold of the sheet, on a horizontal line between the salutation and the address of the addressee of the communication, and having a small part of the lower, prepared end of the lower fold of the sheet left unsealed and conspicuously marked, as a convenient place for opening the communication.

55 2. A communicating form of the kind described, consisting of a sheet of paper, or other material, so cut and arranged that flaps extend outwardly from the sides of the upper fold of the sheet, the flaps being so arranged and prepared, preferably by gumming, that when the sheet is folded, the extending flaps fold backwardly from the front surface of the upper fold of the sheet, and may be fastened or be made to adhere to the back surface of the lower fold of the

sheet, thereby partly sealing the communicating form, the method of folding forming a pocket between the backs of the upper and middle folds of the sheet which may be utilized unsealed or otherwise, having the names and addresses of the transmitter and addressee of the communication exposed to view on the front surface of the upper fold of the letter sheet, having the lower end of the lower fold of the sheet so prepared, preferably by gumming, that when the lower fold of the sheet is folded upwardly against the front surface of the middle fold of the sheet, the lower, prepared end adheres or fastens to the front surface of the letter sheet, substantially along the upper crease of the middle fold of the sheet, on a horizontal line between the salutation and the address of the addressee of the communication, thereby completing the sealing of the communication, having a small part of the lower, prepared end of the lower fold of the sheet left unsealed and conspicuously marked, as a convenient place for opening the communication, having a communication placed, preferably in writing, on the inside surface of the folds of the letter sheet, having the date of the communication placed on the front surface of the letter sheet, preferably at the top of the sheet, as evidence of the time of its execution, and having evidence, preferably a stamp, placed, preferably on the front surface of the upper fold of the sheet, to indicate that the communicating form is entitled to transmission or has been transmitted, including the date thereof.

FRANCIS R. HARDIE.
